UNITED STATES PATENT OFFICE.

ANKER S. LYHNE, OF BRIDGEPORT, CONNECTICUT.

NON-SHORT-CIRCUITING FIBER CASE FOR FLASH-LIGHTS.

1,183,311.

Specification of Letters Patent.

Patented May 16, 1916.

Application filed October 19, 1915. Serial No. 56,738.

To all whom it may concern:

Be it known that I, ANKER S. LYHNE, a citizen of the United States, residing at Bridgeport, county of Fairfield, State of Connecticut, have invented an Improvement in Non-Short-Circuiting Fiber Cases for Flash-Lights, of which the following is a specification.

This invention relates to fiber cases for flashlights and has for its object to avoid the danger of short-circuiting which has existed, so far as I am aware, in all fiber-case flashlights heretofore placed upon the market.

15 It is of course well understood that the fiber flashlight cases known to the trade are closed at the bottom by a metallic cap, the lens is retained in place by a metallic ring, and intermediate the cap and the ring is a 20 metallic circuit-closer secured upon the outer side of the case. The danger of short-circuiting has arisen through the extreme liability of two of these parts to come in contact with a tool, for example in the tool box 25 of a motor car, or with any metallic article which would close the circuit, thus, if the ring and the cap or the ring and the circuit-closer should come accidentally in contact with a metallic article, the circuit would be 30 closed and the battery exhausted. These objections I wholly overcome by providing a structure in which the lens-retaining ring is completely insulated and cannot, under any 35 of the ordinary or extraordinary conditions of use, be brought into the circuit, so that even if a metallic article should come in contact with both the ring and the cap or with the ring and the circuit-closer, no circuit would be established and no harm could 40 result.

In the accompanying drawing forming a part of this specification, Figure 1 is an elevation, partly broken away, of an ordinary standard flashlight case; Fig. 2 a longitudinal sectional view on an enlarged scale, illustrating my present invention; Fig. 3 a detail view showing the electric connection of the contact strip and the battery spring; Fig. 4 a view partly in elevation and partly in section, illustrating a modification of the invention to adapt it to the miners' type of flashlight, and Fig. 5 is a detail sectional view on an enlarged scale, corresponding with Fig. 4.

45 10 denotes the body of the case, which is simply a fiber tube, and 11 the circuit-closer,

which may be of any ordinary or preferred construction, preferably the circuit-closer of my Patent No. 1,122,777, dated Dec. 29, 1914. The battery (not shown) rests upon a spring 50 12, itself secured to a metallic cap 13 which has threaded engagement with the body or with a sleeve 14 riveted or otherwise secured to the body. A contact strip 15 extends from the battery spring to the circuit-closer, 55 and a contact strip 16 extends from the circuit-closer to the reflector, indicated by 17. The contact strips are riveted or otherwise securely fastened to the inner side of the body.

18 denotes the lamp which is carried by the reflector in the usual manner.

19 denotes the lens, and 20 a flanged retaining ring therefor, which has threaded engagement with the body or with a sleeve 70 21 riveted or otherwise securely fastened to the body.

It is an essential feature of the invention that the reflector be effectually insulated from the retaining ring. This I accomplish 80 by causing the reflector to rest upon and be supported by the end of the body and by placing the sleeve, which is engaged by the retaining ring, an appreciable distance below the end of the body, thus making the 85 passage of current from the reflector to the sleeve and ring practically an impossibility.

In the form illustrated in Fig. 2, I provide the upper end of the body with an internal circular shoulder 22, and turn the 90 upper end of the reflector over and downward to form a roll 23 and a flange 24. The lower edge of the flange rests upon the shoulder and the flange is preferably made wide enough so that the lens will rest upon 95 the reflector and not upon the end of the body, so that when the retaining ring is turned down upon the lens, as in Fig. 2, the reflector will be clamped between the lens and the end of the body, the lens being 100 clamped between the flange of the ring and the roll of the reflector and the edge of the flange of the reflector being crowded against the shoulder on the body and against contact strip 16. I thus establish electrical connection 105 between the reflector and the circuit closer, leaving the retaining ring and the sleeve effectually insulated.

In the form illustrated in Figs. 4 and 5, the reflector rests upon and is supported by 110 the end of the body as before, the point of engagement being indicated by 25, and the

upper end of contact strip 16 is turned inward to form a spring arm 26 which is engaged by the reflector. In this form, the lens retaining ring has threaded engagement 5 with the outer end of a head 27 and the reduced inner end of the head has threaded engagement with the body or with sleeve 21. The lens, which is relatively much larger than in the other form, rests upon an insulating ring 28 which is interposed between the edge of the reflector and the threaded outer end of the head, thus effectually insulating the retaining ring. When the head 10 is turned down upon the body, as in Fig. 5, 15 the end of the body will engage the reflector at the point indicated by 25, and the reflector

will be clamped between the end of the body and the lens.

Having thus described my invention I claim:

A flashlight case comprising a fiber body having an internal shoulder near its outer end and a metallic sleeve secured to the body, the front end of the body extending beyond the sleeve, a reflector having a roll 20 and also having a flange engaging the shoulder, a lens resting upon the roll, and a flanged lens-retaining ring having threaded engagement with the sleeve.

In testimony whereof I affix my signature. 25

ANKER S. LYHNE.
